(74) *Attorney, Agent, or Firm* — Cantor Colburn LLP

(57) **CLAIM**

The ornamental design for a television receiver, as shown and described.

DESCRIPTION

FIG. 1 is a front perspective view of a television receiver showing our new design in a screen-retracted configuration; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a rear perspective view thereof; FIG. 9 is another front perspective view thereof, showing an environment of use in which the GUI displayed on the screen is visible through the front surface of the television receiver and the GUI is shown in dot-dash broken lines; FIG. 10 a front perspective view of a television receiver showing our new design in a screen-deployed configuration; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; and, FIG. 17 is another front perspective view thereof, showing an environment of use in which the GUI displayed on the

(Continued)

screen is visible through the front surface of the television receiver and the GUI is shown in dot-dash broken lines. The broken lines in the figures show portions of the television receiver which form no part of the claimed design.
